UNITED STATES PATENT OFFICE

WILLIAM F. SCHACHT, OF HUNTINGTON, INDIANA

DESIGN FOR A LABEL

Application filed November 18, 1932. Serial No. 46,058. Term of patent 7 years.

To all whom it may concern:

Be it known that I, WILLIAM F. SCHACHT, a citizen of the United States, residing at Huntington, county of Huntington, State of Indiana, and whose post-office address is c/o Schacht Rubber Mfg. Co., in said city, have invented a new, original, and ornamental Design for a Label, of which the following is a specification, reference being had to the accompanying drawing, constituting a part thereof.

The figure is a plan view of a label showing my new and ornamental design.

I claim:

The ornamental design for a label, substantially as shown.

In testimony whereof I have hereunto subscribed my name this 16th day of November, 1932.

WILLIAM F. SCHACHT.
